APPARATUS FOR REPAIRING CONTAINERS
FOR HIGH TEMPERATURE MATERIAL

Alfred Osolin, Shaker Heights, Ohio

Application November 13, 1936, Serial No. 110,769

5 Claims. (Cl. 266—39)

This invention relates generally to the repairing of holes in walls subjected to high temperatures, but is particularly concerned with the repairing or patching of holes in blast-furnace slag ladles. Such ladles are commonly made of cast metal, and are subject to leaks due to localized portions of their walls having a tendency to break out in pieces in such manner as to leave holes. The present inventor intends to provide an improved manner of patching such holes, the patches applied in accordance with the teachings of the prior art being quite insecure and providing but a temporary remedy.

Referring to the accompanying drawing:

15 Figure 1 is a vertical section of a blast-furnace cinder ladle patched in accordance with the present invention.

Figures 2 and 3 are sectional and elevation views of one of the patches.

20 Figures 4 and 5 are sectional and elevation views of another of the patches.

The drawing illustrates a cast metal blast-furnace slag ladle 1. The wall of this ladle is made of solid cast metal, and extreme temperature changes subject it to severe stresses due to expansive and contractive effects. These stresses are particularly severe when they become concentrated at one point or another of the ladle wall as they frequently do, due to its integrity and rigidity. Since the metal of the wall is repeatedly heated above its critical range its crystalline structure changes so that the situation is further aggravated by the metal actually becoming weaker. These various factors all contribute to the trouble with which the present invention is concerned, namely, the breaking away of localized portions of the ladle wall so as to leave holes. Quite naturally it is desirable to repair these holes so that the service life of the ladle may be prolonged.

40 According to the prior art, this may be done by the insertion of solid metal pieces which are held in place by riveting, bolting or welding. These pieces, however, also undergo the same destructive influences. As a result they do not stay in place very long. As they become weaker they at the same time attempt to change their shape and, due to the large masses of metal represented by each, sufficient stresses are created to tear them loose from whatever fastening may be used.

45 To illustrate the principles of the present invention, the drawing shows two holes A and B in the wall of the ladle 1. These holes are each filled with a plurality of relatively thin metal pieces in the form of metal plates or sheets 2

arranged parallel and in edgewise relationship respecting the interior of the ladle. These plates or sheets are cut in such lengths and are of such widths as to fill the holes A and B.

5 They are mounted by plates 3 fixed to the outside of the ladle by riveting and welding, and in which there are a plurality of slots or openings 4 arranged so that at least one of the openings registers with each of the plates or sheets 2. Welding metal is deposited through these openings 4 so as to connect the outer edges of the plates or sheets 2 with the plates 3.

10 It is to be noted that the plates or sheets 2 are individually free excepting for their connections with the plates 3. Therefore, when their shapes 15 tend to change due to thermal effects, the resulting stresses are relatively small, being in each instance the stress caused by what is a relatively small piece of metal as compared to the area of the patch as a whole. Since the plates or sheets are separate from one another, there is no chance for an accumulation of stresses such as there is when a solid piece of metal is used. For practical purposes a patch of the character disclosed may be considered as absolutely permanent.

20 Although the plates or sheets are illustrated as straight, flat sections, the same results may be obtained by the use of other sections. Furthermore, it may in some instances be desirable to slightly space the various pieces constituting the patch. Other means for mounting the pieces may be used. The fundamental idea is the use of a plurality of relatively thin pieces of metal arranged to fill the hole to be patched and capable of individual movement during expansion and contraction, whereby to prevent stress values or concentrations sufficient to disrupt the patch.

25 I claim:

30 1. A patch for a hole in a container for high temperature material including a plurality of pieces of metal filling the hole, a mounting fixed to the outside of the container over the hole and means for connecting each of said pieces to said mounting.

35 2. A patch for a hole in a container for high temperature material including a plurality of pieces of metal filling the hole, a mounting fixed to the outside of the container over the hole and means for connecting each of said pieces to said mounting, said pieces being in the form of plates or sheets arranged in edgewise relationship respecting the interior of the container and individually free from one another excepting for their connection with said mounting.

3. A patch for a hole in a container for high temperatured material including a plurality of pieces of metal filling the hole, a mounting fixed to the outside of the container over the hole and means for connecting each of said pieces to said mounting, said pieces being in the form of plates or sheets arranged in edgewise relationship respecting the interior of the container and individually free from one another excepting for their connection with said mounting, the latter being in the form of a plate having at least one opening registering with each of said plates or sheets and through which welding metal is deposited to connect the edges of the latter with said mounting.

4. A method of patching a hole in a container for high temperatured material, including arranging a plurality of metal plates or sheets in the hole of such lengths as to substantially fill the latter and in edgewise relationship respecting the interior of the container, fixing a plate to the outside of the container over the hole

and connecting the outer edges of said plates or sheets with said plate.

5. A patch for a hole in a container for high temperatured material including a plurality of pieces of metal filling the hole, a mounting fixed to the outside of the container over the hole and means for connecting each of said pieces to said mounting, said pieces being in the form of plates or sheets arranged in edgewise relationship respecting the interior of the container and individually free from one another excepting for their connection with said mounting, the latter being in the form of a plate having at least one opening registering with each of said plates or sheets and through which welding metal is deposited to connect the edges of the latter with said mounting, and said plates or sheets being of sufficient thinness to prevent forces caused by thermal distortion of the same from freeing them from their connection with said mounting. 20

ALFRED OSOLIN.
